UNITED STATES PATENT OFFICE.

FRED R. BELT, OF CHICAGO, ILLINOIS, ASSIGNOR TO FRED R. BELT COMPANY, OF CHICAGO, ILLINOIS, A CORPORATION OF ILLINOIS.

MINER'S LAMP.

Application filed May 2, 1923. Serial No. 636,110.

More particularly my invention relates to a miner's lamp of the type wherein acetylene gas is generated by the controlled application of water to calcium carbide.

5 Lamps of the class described generally comprise a water chamber, a carbide chamber, a valve controlled passageway connecting the carbide chamber with the water chamber, and a passageway connecting the carbide chamber with a suitable burner carried by the lamp.

Heretofore it has been the usual practice to manufacture the major portion of a miner's lamp from sheet metal, which is 15 spun or pressed to give the desired form to the several parts of the lamp. The parts so formed are generally brazed or soldered to each other, and all lugs or the like are either soldered directly to the outer surface 20 of the lamp or held in apertures formed in the walls of the lamp, the joints being afterwards soldered to prevent leakage of gas from the lamp.

My invention contemplates a miner's 25 lamp constructed chiefly of die castings. In a lamp so constructed, it is not necessary to braze or solder numerous joints, and all lugs or the like can be formed integral with the castings which enclose the several chambers.

The main object of my invention is to provide a miner's acetylene lamp of improved construction.

Other and more specific objects of my invention are to provide a lamp of the class described which has improved valve means for controlling the application of the water to the calcium carbide; which has an improved cap for closing the filling opening of the water chamber; which has improved means for securing the reflector to the lamp; which has improved means for preventing slaked carbide from passing to the burner; and which has improved means for holding the burner.

Other objects of my invention will become apparent as the detail description progresses, reference being had to the accompanying drawing, wherein—

50 Fig. 1 is a central longitudinal section taken through my improved miner's lamp.

Fig. 2 is a plan view of my improved miner's lamp.

55 Fig. 3 is a section taken on line 3—3 of Fig. 1.

Fig. 4 is a section taken on line 4—4 of Fig. 1.

Fig. 5 is a perspective view of valve means which form a part of my improved miner's lamp, and

60 Fig. 6 is a perspective view of another form of valve having the same characteristics as those attending the valve shown in Fig. 5.

65 In the drawing, the reference characters 10 and 11 designate the water chamber and the carbide chamber respectively of my improved miner's lamp. The water chamber 10 is contained within a die casting 12 having a substantially cylindrical wall 13 and 70 a bottom wall 14 formed integrally with the cylindrical wall 13. A cover 15 is seated upon an annular shoulder 16 formed in the cylindrical wall 13 and is rigidly secured in place by means of a plurality of screws 17, 75 a gasket 18 being interposed between the cylindrical wall 13 and the cover 15. Formed integrally with the cylindrical wall 13 and the bottom wall 14 and extending 80 downwardly therefrom is an annular flange 19 having an internal thread 20 adapted to receive the external thread 21 of a die casting 22 which encloses the carbide chamber 11. The die casting 22 is provided with an outwardly extending annular flange 23 to 85 provide means whereby a gasket 24 may be held between the die casting 12 and the die casting 22 to prevent a leakage of acetylene gas from the carbide chamber 11.

90 Disposed within the water chamber 10 is a tube 25 having its upper end encircling a boss 26 formed on the inner surface of the cover 15, and its lower end seated in a circular depression 27 formed in the bottom wall 14 of the die casting 12. The tube 25 95 is provided at its upper end with a vent opening 28 and at its lower end with an aperture 29 which permits water to flow from the water chamber 10 to the interior of the tube and then into a water tube 30 100 rigidly secured in a boss 31 formed integrally with the bottom wall 14. The water tube 30 is disposed concentrically with respect to the tube 25. It will be noted that the upper end of the water tube 30 is threaded or 105 knurled as at 32. This is to facilitate the manufacture of the lamp as the water tube 30 is preferably placed in the mold in which the die casting 12 is formed, the molten metal being permitted to engage the threaded 110

or knurled portion 32 of the water tube to rigidly secure the water tube to the die casting.

The means for controlling the application of water to the calcium carbide placed in the carbide chamber 11 comprises a valve 33 adapted to seat against the lower end of the water tube 30. The valve 33 is provided with a valve stem 34, having an axis of rotation coincident with the axes of the tube 25 and the water tube 30. As shown in Fig. 1, the lower end of the valve stem 34 is reduced in diameter to provide a shoulder 35 against which the valve 33 rests, the reduced portion of the valve stem terminating at the outer side of the valve and being riveted over as at 36 to rigidly secure the valve to the valve stem. The upwardly extending end of the valve stem terminates in a portion 38 of enlarged diameter, which is threaded into the cover 15, the outer end of the valve stem having a rosette 39 formed thereon adapted to be engaged by a rosette 40 formed upon a valve lever 41. It will be readily understood that the valve lever 41 may be secured in a plurality of adjusted positions relative to the valve stem 34, the means for so securing the valve lever to the valve stem comprising the rosettes 39 and 40, and a screw 42 passing through the valve lever 41 and threaded into the valve stem 34. The valve 33 may be moved toward and away from its seat upon the lower end of the water tube 30 by rotating the valve stem 34, the amount of displacement of the valve 33 relative to the water tube 30 from any given angular displacement of the valve stem being determined by the lead of the threads formed upon the enlarged portion 38 of the valve stem 34.

As shown in Fig. 2, I provide a pair of stops 44 and 45 which are arranged to lie in the path of the valve lever 41 and to thus limit the angular displacement of the valve stem 34. The mechanism is preferably so adjusted that when the valve lever 41 is in engagement with the stop 44, the valve 33 will be seated against the lower end of the water tube 30 to prevent the flow of water from the water tube to the carbide contained within the carbide chamber 11. By angularly displacing the valve stem 34 in a clockwise direction (Fig. 2) the valve may be moved away from its seat upon the water tube 30 a distance which will permit the desired flow of water to the carbide in the carbide chamber. The maximum flow of water is of course determined by the stop 45. To hold the valve 33 in an adjusted position relative to the water tube 30 I have provided a plurality of lugs 46 formed upon the upper surface of the cover 15 and arranged concentrically with respect to the axis of rotation of the valve stem 34. The valve lever 41 is somewhat flexible and is provided with

a bead 47 which is adapted to engage the lugs 46. It is apparent that the valve lever 41 will yieldingly hold itself in any adjusted position relative to the lugs 46.

Referring now to Figs. 1 and 5, it will be noted that the valve 33 is provided with a pair of diametrically disposed lugs 50 which are arranged to engage or to lie in close proximity to the outer surface of the water tube 30. The lugs 50 are adapted to agitate any slaked carbide which may gather around the lower end of the water tube 30 or the valve 33. The lugs 50 will of course tend to wipe clean the outer surface of the lower end of the water tube 30 when the valve 33 is rotated. The main body portion of the valve 33 is also adapted to agitate carbide surrounding the valve, as it is provided with two flattened surfaces 51, against which the slaked carbide may collect and from which the carbide will be displaced when the valve is rotated. In Fig. 6 I have shown a valve 33^a which may be substituted for the valve 33 as it too is adapted to seat against the lower end of the water tube 30. The valve 33^a is provided with three symmetrically arranged lugs 50^a which resemble and have the functions of the lugs 50 of the valve 33. In some instances it may be advantageous to employ the valve 33^a in place of the valve 33.

The acetylene gas which is generated in the carbide chamber 11 is led to a burner 53 by way of a passageway 55 molded in the die casting 12. The burner 53 is seated in a burner holder 54 which is threaded into the wall of the outer end of the passageway 55. The burner 53 is seated at the inner end of a central aperture 56 formed in the burner holder 54, the central aperture 56 being of substantially the same diameter as the burner 53 and forming an open chamber directly in front of the burner. Therefore, any flame attending the burner will lie wholly or partly within the aperture 56 and will be protected from air currents which tend to extinguish it. Incidentally, I provide the outer face of the burner holder 54 with a pair of diametrically disposed slots 58 which are adapted to be engaged by a coin or a suitable tool when the burner holder is to be removed from the lamp to permit replacement of the burner, or cleaning of the lamp.

At this point in the description it is well to point out that the burner holder 54 is adapted to secure a reflector 60 to the lamp, the burner holder 54 being provided with an annular flange 61 which engages the marginal edges of an aperture 62 formed in the reflector, and which holds the reflector firmly against a boss 63 cast integral with the die casting 12. In addition to this means for securing the reflector to the lamp I find it advantageous to provide a pair of braces 64, each of which has one end thereof rigid-

ly secured to one of a pair of lugs 65 formed integral with the cylindrical wall 13, and the other end thereof adapted to engage a beaded edge 66 formed upon the outer edge 5 of the reflector 60.

The braces 64 are secured to the lugs 65 by screws 67. The reflector engaging ends of the braces 64 normally make angles with the ends secured to the lamp more obtuse 10 than those shown in Fig. 2 so that they must be sprung outwardly when the reflector is placed between them. This construction permits the braces to hold the reflector securely in place whenever the burner holder 15 54 is removed for the reasons given above.

The aforementioned passageway 55, which is adapted to connect the burner 53 with the carbide chamber 11, extends downwardly from the burner to the carbide chamber, but 20 does not open directly into the carbide compartment of the chamber, as an apertured baffle plate 69 is arranged transversely of the carbide chamber 11, the baffle plate being spaced a comparatively small distance 25 from the bottom wall 14 of the water chamber 10. It will be noted that the baffle plate 69 is positioned against the bottom edge of the downwardly extending wall 70 formed integral with the bottom wall 14, and that 30 the downwardly extending wall 70 is arranged to divide into two parts that portion of the carbide chamber 11 which lies between the bottom wall 14 and the baffle plate 69 (Fig. 3). The passageway 55 opens 35 into one of the compartments thus formed by the wall 70, as indicated at 71, the other compartment, which is designated by the reference character 72, being connected to the carbide compartment 73 of the carbide 40 chamber by means of the apertures 74 of the baffle plate 69. A plurality of grooves 75 in the under surface of the wall 70 connect the compartment 72 with the compartment 71. The baffle plate 69 is rigidly secured to 45 a sleeve 76 which is in turn rotatably and slidably journaled upon the downwardly extending lug 31 formed integral with the bottom wall 14 of the die casting 12. The sleeve 76 is slotted to provide a plurality of 50 spring members 77 (Fig. 3) which are adapted to frictionally engage the lug 31 to hold the baffle plate 69 in a position wherein it rests against the bottom surface 55 of the wall 70, as shown in Fig. 1.

It will be readily understood that the acetylene gas generated from the calcium carbide, which may be placed in the carbide compartment 73 of the carbide chamber 11, will flow through the apertures 74 of the baffle plate 69 into the compartment 72, which may be termed a gas chamber. From 60 the gas chamber or compartment 72 the gas will flow through the grooves 75 in the wall 70 to the compartment 71. The gas will 65 then of course flow through the passageway

55 to the burner 53. The advantage of this construction is apparent. The baffle plate 69 and the wall 70 cooperate to prevent the passage of particles of carbide to the burner 53, and thus prevent the aperture in the burner 70 from becoming choked or clogged with carbide.

The apertures 74 in the baffle plate 69 are preferably spaced equal distances from the rotary axis of the valve stem 34 so that they 75 may be engaged in turn by a button 80 cast on the undersurface of the wall 70. When the slaked carbide is being removed from the carbide chamber, the die casting 22 having been unscrewed from the die casting 12, 80 the operator may rotate the baffle plate 69 a few times to dislodge the slaked carbide adjacent the outer edge of the baffle plate and to permit the button 80 to enter the several apertures 74, thus driving out any 85 carbide which has lodged in the apertures.

As shown in Figs. 1 and 2, water may be supplied to the water chamber 10 through a filling opening 81 formed in the cover 15. A cap 82 is provided for the filling opening 81, 90 the cap being pivotally secured by means of a pin 83 to a pair of lugs 84 cast integral with the cover 15. A disk 85, detachably secured in the cap 82 and forming a bottom wall therefor, has its edge slotted as at 86. 95 The top wall of the cap is provided with a vent opening 87. A substantially cylindrical chamber 88 formed in the cap 82 and having its axis coincident with the axis of the vent opening 87 accommodates a metallic ball 89 having a diameter somewhat less than the diameter of the chamber. The cylindrical surface of the chamber 88 comprises a wall 90 cast integral with the top wall of the cap and having a plurality of 100 grooves 91, which, together with the grooves 86 in the disk 85, permit the vent opening 87 to admit air to the water chamber 10 whenever water is being withdrawn from the water chamber for application to the 105 calcium carbide. However, if a comparatively large quantity of water should be inadvertently fed to the calcium carbide, and if the comparatively large quantity of acetylene gas then generated should attempt to force its way out of the carbide chamber by passing through the water tube 30, the apertures 28 and 29 in the tube 25, and then through the apertures 86 and 91 associated 110 with the cap, the gas could not escape through the vent opening 87, as the gas would raise the ball 89 into a position wherein it seated itself in the vent 87. This construction also prevents the gas from forcing out a spray of water through the vent 115 opening.

I have provided means whereby the lamp may be detachably secured to the shield which is usually affixed to the miner's cap, the means comprising a hook 93 having one 120 125 130

end thereof rigidly secured in a lug 94 cast integral with the die casting 12. The portion of the hook 93 which passes through the lug 94 is substantially rectangular in cross section and is received in an aperture of like cross section, the aperture being formed in the lug during the die casting operation. As shown in Fig. 1, one end of the hook is bent to lie against the lug, and serves to rigidly secure the hook to the lug.

The die castings 12 and 22 are each preferably provided with a plurality of ribs or fins 100 and 101 respectively, which are adapted to radiate the heat flowing into the castings from the flame attending the burner. This construction is not analogous to the ribs which are usually struck into the walls of lamps manufactured mainly from sheet metal, as in the latter instance the radiating surface of the lamp is not materially increased.

In the operation of the device, a suitable quantity of calcium carbide is placed in the carbide chamber 11 and the water chamber 10 is filled with water. The valve 33 is then secured in an adjusted position relative to the water tube 30 by means of the valve lever 41. As soon as the water comes in contact with the calcium carbide, acetylene gas is generated which flows through the apertures 74 of the baffle plate 69, the grooves 75 of the wall 70 and through the passage 55 to the burner 53, where the gas may be ignited by means of the pyrophoric igniter 102.

It will be readily understood that should the valve 33 become worn and fail to seat upon the lower end of the water tube 30 when the valve lever 41 is in engagement with the stop 44, the operator may easily readjust the mechanism by removing the screw 42 and angularly displacing the valve lever 41 relative to the valve stem 34. After the proper position of the valve lever 41 relative to the valve stem 34 has been determined, the valve lever 41 may again be rigidly secured to the valve stem by means of the screw.

I am aware that changes in the form, construction and arrangement of parts may be made without departing from the spirit and without sacrificing the advantages of the invention and I reserve the right to make all such changes as fairly fall within the scope of the following claims.

I claim:

1. In a lamp of the class described, a water chamber, a carbide chamber, a cylindrical tube having one end connected with the water chamber and the other end opening into the carbide chamber, a valve seating against the last mentioned end of the tube, and a plurality of spaced means carried by the valve and engaging the outer cylindri-

cal surface of the tube for dislodging slaked carbide adhering to the tube.

2. In a lamp of the class described, a water chamber, a carbide chamber, a cylindrical tube having one end connected with the water chamber and the other end opening into the carbide chamber, a valve seating against the last mentioned end of the tube and having a lug disposed to engage the outer cylindrical surface of the tube, and means for rotating the valve.

3. In a lamp of the class described, a water chamber, a carbide chamber, a passageway between the water chamber and the carbide chamber, a valve for controlling the passageway, a valve lever, the valve and lever having interengaging rosettes formed thereon, and means holding said rosettes in engagement, said means permitting adjustment of said lever in respect to said valve.

4. In a lamp of the class described, a carbide chamber, a passage communicating with the carbide chamber, an apertured revoluble plate disposed in the carbide chamber to prevent carbide from entering the passageway, and means adapted to enter and clean the aperture in the plate when the plate is revolved.

5. In a lamp of the class described, a carbide chamber, a baffle plate arranged transversely of the carbide chamber and adjacent the top thereof, a wall projecting downwardly from the top of said chamber and having its bottom edge contacting with said baffle plate, said baffle plate having an aperture therein arranged on one side of said wall, a burner having a passageway opening into said carbide chamber on the opposite side of said wall from said aperture and said wall having an opening extending therethrough whereby gas may pass from said chamber through the aperture in said plate, through said wall and said passageway.

6. In a lamp of the class described the combination with a carbide chamber comprising a substantially cylindrical casing of a water chamber comprising a side wall, a bottom wall and an annular flange formed in one piece of material, said flange making threaded engagement with the cylindrical casing of the carbide chamber, a wall depending from said bottom wall, said depending wall forming one side of a passage communicating with the carbide chamber, and having an opening therein forming a gas outlet, and a baffle plate disposed beneath said depending wall and co-operating therewith to form said passage.

7. In a lamp of the class described, a carbide chamber, a water chamber secured thereto and comprising a side wall, a bottom wall and a wall depending from said bottom wall, all formed of one piece of material, a boss on said bottom wall and ex-

tending into said carbide chamber and an apertured plate secured on said boss and co-operating with said depending wall to form a passageway for gas from said carbide chamber.

8. In a lamp of the class described, a carbide chamber, a water chamber, a wall separating said chambers, a baffle plate in said carbide chamber and secured in spaced relation from said wall, said baffle plate closing said carbide chamber, and a wall depending from said first named wall and co-operating with said baffle plate to form a passage, for the purpose set forth.

9. In a lamp of the class described, a carbide chamber, a water chamber, a wall separating said chambers, a baffle plate in said carbide chamber and secured in spaced relation from said wall, and a wall depending

from said first named wall and co-operating with said baffle plate to form a passage, said baffle plate being provided with apertures for the passage of gas from said carbide chamber and said depending wall being provided with apertures communicating with a burner, for the purpose set forth.

10. A miner's acetylene lamp having a cast metal chamber provided with an external integral lug having an upright opening extending through the top and bottom thereof, and a replaceable supporting hook having a shank detachably extending through the opening in the lug, the shank and the opening in the lug having non-circular mutually engaging wall portions to prevent rotation of the shank, and displacement means to hold the shank in the lug.

FRED R. BELT.
